Inventor

Moses S. January

By *A. Randolph, Jr.* Attorney

UNITED STATES PATENT OFFICE.

MOSES S. JANUARY, OF DOUGLAS, ARIZONA.

CATAMENIAL SACK.

Application filed March 26, 1919. Serial No. 285,213.

To all whom it may concern:

Be it known that I, MOSES S. JANUARY, a citizen of the United States, residing at Douglas, in the county of Cochise and State 5 of Arizona, have invented certain new and useful Improvements in Catamenial Sacks; and I do hereby declare the following to be a full, clear, and exact description of the invention, such as will enable others skilled 10 in the art to which it appertains to make and use the same.

My invention relates to improvements in catamenial sacks.

An important object of this invention is 15 to provide a catamenial sack having means for effectively preventing soiling of the garments during the menstrual period.

A further object of the invention is to provide a device of the character described, 20 which is of highly simplified construction, convenient to wear and highly sanitary in use.

A further object of the invention is to provide a device of the character described, 25 which by reason of its simplified construction and the cheapness of manufacture, it will successfully compete with numerous similar devices in a highly crowded art.

Other objects and advantages of this in- 30 vention will be apparent during the course of the following description.

In the accompanying drawings, forming a part of this specification and in which like numerals are employed to designate like 35 parts throughout the same,

Figure 1 is a side elevation of a device embodied in my invention showing the same suspended from a belt,

Figure 2 is a plan view of the same, and 40 Figure 3 is a longitudinal section through a sack embodied in the same.

In the drawings wherein for the purpose of illustration is shown the preferred embodiment of my invention, the numeral 5 designates a belt preferably of elastic construc- 45 tion and adapted to be worn about the waist.

The belt 5 has a plurality of straps 6 connected therewith through the medium of co-acting hooks and eyes 7. The lower ends of 50 the straps 6 are stitched or otherwise secured to a sack or pouch generally designated by the number 7. The element 7 includes an upper and lower portion 8 and 9 respectively.

The upper side 8 is provided with an oval shaped opening 10 for the obvious purpose 55 of receiving the waste matter. As illustrated in Figure 2, the portions 8 and 9 are open on their sides and connected at their ends. An absorbent element 11, preferably pure sheet wool, is adapted to be disposed between the 60 upper and lower portions 8 and 9. A covering of cheese cloth or the like may be secured about the absorbent material for forming a strainer element. The portions 8 and 9 are preferably of a soft rubber or other imper- 65 70 75

vious material. A sheet of oil cloth 12 may be arranged between the absorbent element 11 and the lower portion 9 for the purpose of preventing the matter from the absorbent element 11 escaping.

In preparing the device for use, it will be apparent that the oil cloth layer 12 is inserted between the upper and lower layers 8 and 9 and the absorbent element 11 ar- 70

anged thereon.

While I have shown and described the preferred embodiment of my invention, it is understood that I may make such minor changes in arrangement and construction of parts, as will remain within the spirit of the 80 invention and the scope of the appended claim.

Having thus described my invention, what I claim is:

A catamenial sack having an upper and a 85 lower layer, said lower layer being of im- pervious material, suspending means for the sack adjacent each end thereof, stitching at each end of the sack securing the layers to- 90 gether and the suspending means thereto, said stitching of the different ends being in deflected rows and spaced apart to provide a pad-insert opening between the sheets at a side thereof of less length than the greatest distance between said means, the upper layer 95 forming a means to overlap and retain the pad on the lower layer, and said upper layer having an opening therethrough to expose the pad retained by the sacks.

In testimony whereof I affix my signature 100 in presence of two witnesses.

MOSES S. JANUARY.

Witnesses:

OLIVER J. HAYES,
MATTIE WILHITE.
